UNITED STATES PATENT OFFICE.

ROBERT RISCH, OF MILWAUKEE, WISCONSIN.

ATTACHMENT FOR DIGGING IMPLEMENTS.

1,353,494.

Specification of Letters Patent. Patented Sept. 21, 1920.

Application filed August 16, 1919. Serial No. 317,972.

To all whom it may concern:

Be it known that I, ROBERT RISCH, a citizen of the United States, and resident of Milwaukee, in the county of Milwaukee and 5 State of Wisconsin, have invented new and useful Improvements in Attachments for Digging Implements, of which the following is a description, reference being had to the accompanying drawings, which are a part 10 of this specification.

The present invention relates to certain new and useful improvements in attachments for spades or forks, and has for one of its 15 objects to provide an attachment of this character which will materially reduce the labor and effort required in digging.

Another object of the present invention is to provide an attachment of the character 20 for the purpose set forth which may be readily applied to spades or forks now in use, or to spades or forks at the time of their manufacture.

With the above and other objects in view which will appear as the description proceeds, my invention resides in the novel 25 construction, combination and arrangement of parts substantially as hereinafter described and more particularly defined by the appended claim, it being understood that 30 such changes in the precise embodiment of the herein disclosed invention may be made as come within the scope of the claim.

In the accompanying drawing, I have 35 illustrated one complete example of the physical embodiment of the herein disclosed invention constructed according to the best mode I have so far devised for the practical application of the principles thereof, and in which:

40 Figure 1 is a perspective view of a spade and a portion of the handle illustrating my attachment as secured thereto.

Fig. 2 is a view similar to Fig. 1 of a fork having my attachment secured thereto.

45 Fig. 3 is a perspective view of the attachment detached, and

Fig. 4 is a perspective view of the channeled securing member employed in connection with my attachment when the same is 50 used with a fork.

Referring now more particularly to the accompanying drawing, my invention consists of a metal bracket 5 of the necessary width and thickness bent at the proper an-

gle as at 6 to secure the greatest amount of 55 leverage when properly attached to a spade or fork with the means provided for attaching. The angle 6 of the bracket is such that the portion 6' thereof will be at substantially right angles with respect to the spade 60 or fork as clearly shown in Figs. 1 and 2.

The ends of the bracket are directed laterally and then folded upon themselves as at 7 and provided with spaced apart apertures 8 for receiving the ends of U-clips 9. The 65 clips 9, as best shown in Fig. 1, engage about the adjacent portions of the spade handle 10 to thus clearly fasten the bracket thereto.

In use, the spade is forced into the earth 70 in the usual manner. When raising the same, however, instead of lifting it, the spade handle is pressed downwardly until the bend 6 of the bracket rests upon the surface of the earth. The width and rounded 75 corner prevents its sinking into the earth, and thus acts as a fulcrum for the spade handle permitting the work to be done with less effort than is required without the bracket attachment.

When used with a fork, the bracket attachment is provided with a foot rest 11 which supplies a foothold for the user. This foot rest fits over the top of the fork and furnishes a secure foothold in digging, 85 where otherwise the foot slips off the top rounded portion of the fork. The foot rest 11 is formed of a single length of metal having a channel 12 therein engaging the top of the fork and provided with a recess 90 13 medially of its ends for engagement about the base of the fork handle 10. As clearly shown in Fig. 4, the recess 13 is formed by striking rearwardly therefrom a portion or lip 14 which is bent or folded to 95 lie against the wider side 15 of the member 11, and the lip 14 and the side 15 have therein an opening 16 through which passes a bolt 17 for securing the lower end 7 to the fork.

When used on a fork, the lower U-shaped 100 clip 9 is dispensed with and the bolt 17 serves to retain the foot rest 11 in position and also to secure the lower end of the bracket attachment to the fork.

The use of the same upon the fork is identical with its use as described in connection with the spade.

What I claim as my invention is:

An attachment for digging implements comprising a bracket consisting of a strip of metal having a horizontal portion and an upwardly and inwardly inclined portion, reinforced ends on said bracket, means securing the upper end of said bracket to the handle of the digging implement, a plate having a top channel portion engageable

over the top of the digging implement and having a cutaway portion for the handle of said implement, and common means for securing said plate and the lower end of said bracket to the implement.

In testimony whereof, I affix my signature.

ROBERT RISCH.
